UNITED STATES PATENT OFFICE.

WILLIAM SEATON, JR., OF NEW YORK, N. Y.

MECHANICAL STOKER.

No. 819,937.

Specification of Letters Patent.

Patented May 8, 1906.

Application filed April 14, 1903. Serial No. 152,575.

To all whom it may concern:

Be it known that I, WILLIAM SEATON, Jr., a citizen of the United States, and a resident of New York city, in the county of Richmond 5 and State of New York, have made certain new and useful Improvements in Mechanical Stokers, of which the following is a specification.

Stokers with which I am acquainted are 10 defective either mechanically or thermally—that is, many of them are of defective mechanical design—having many parts subject to the action of the fire and, though reasonably efficient in producing combustion, get 15 out of order and take an excessive power to operate. Those thermally defective obstruct the fire-pit, so that the draft is interfered with and its distribution affected to such an extent as to impair the efficiency of the furnace. 20 A typical one of these stokers is an ordinary chain grate running over sprockets; but this, as is manifest, has a great number of joints which soon corrode and increase the friction of the apparatus. Other serious defects are 25 its obstruction of the access of air to the under side of the fire (since it is manifest that the same part of the grate is in contact with the same part of the fire throughout its traverse of the combustion-chamber) and lack of 30 means of agitation of the fire at the proper times.

The chain grate is merely an example of old constructions upon which I aim to substantially improve by the devices and method 35 of operation which I herein disclose. Other stokers have somewhat similar defects or disadvantages. For these devices I substitute sets of grate-bars which are advanced together and retracted in alternation, one of 40 the sets being retracted while another is stationary. To avoid breaking up the fire to too great extent, thus impairing its efficiency, the bars which are being retracted are dropped away from the fire during the motion of retraction. When they are brought back to 45 their original longitudinal position, they are raised and again come in contact with the bed of coke or coal, and after both sets advance again longitudinally in the same plane the 50 other set of bars is lowered, so that the fire now rests on the ones first retracted. This operation is repeated by the sets of bars in alternation, the result being the gradual advance of the entire bed of the fire from the

front to the back of the furnace. It is found 55 in practice that the coke or coal soon after it enters the furnace packs or cakes, so that every alternate bar of the grate may be lowered as much as is necessary to clear and avoid disruption of the fire-bed during retraction. The caking action referred to makes the coal substantially arch over the openings caused by the withdrawal of one set of bars, so that these bars may be retracted without retrogression of the coal. If it should 60 happen with such material as finely-divided anthracite coal that some few particles adhered to the grate-bars with more friction than to the coal-bed above, devices are provided which will interrupt their retrogression during the period of retraction. 70

An incidental advantage, and one of importance in the practice of the invention, is that the grate-bars may, if desired, be larger and more substantial than those hitherto in 75 use, and since the coal in its active state of combustion does not remain in constant contact with them the bars will not burn out so soon. I believe it to be new with me to provide any mechanism which will alternately 80 expose by sections the entire under surface of the fire to the action of the draft and will also advance the fire properly through the furnace without manual interference.

An important and valuable feature of the 85 invention is in the carrying forward of the bed of the fire substantially without friction over the grate as distinct from pulling, pushing, or rocking the coal along. The alternation of position of the fire-supporting parts by 90 which the points of support are shifted and those parts which have been theretofore excluded from the draft are exposed to it enables me to obtain greatly-improved combustion and to avoid the tendency of clinker 95 to "set" upon the bars. This arrangement also has the advantage of permitting the portion of the grate in contact with the fire-bed to be periodically subjected to the action of the draft, so that it is cooled below the excessive temperature to which it is often subjected and its life is greatly prolonged. 100

As coal progresses through a furnace a progressively-increasing amount of agitation becomes necessary in order to get efficient combustion. This is provided by my improved device. It will be observed that when the coal first enters the furnace it is carried along 105

substantially without agitation and cokes in the heat of the furnace, the gases being carried by the draft toward the stack and consumed. As the bed of partially-cooked coal 5 passes on it ignites and generates intense heat. As the ash accumulates the fire becomes more friable, and as the grate-bars descend the fire now begins to follow them, while at the back of the furnace, beginning at 10 about the line of support for the grate-bars, instead of the latter falling away from the fire they are slightly thrust up into it, so that the ashes are completely disintegrated by the retraction of the bars and sift through into the 15 ash-pit.

The accompanying drawings show my invention.

In the drawings, Figure 1 is a side elevation, partly in section, on line 1 1 of Fig. 2, 20 the slides M (hereinafter referred to) not being shown. Fig. 2 is a plan with certain parts omitted and with the sustaining-frame of the machine shown partly in section. Fig. 3 is an end elevation with one set of grate-bars and their supporting projections omitted. Figs. 4 and 4^a are perspective details of part 25 of the operating mechanism. Fig. 5 is a detail of the cylinder-support. Fig. 6 is a diagram illustrating the motion of selected 30 points upon the front parts of the grate-bars. Fig. 7 is a perspective detail of the ash-conveying device.

Referring now to Figs. 1, 2, and 3, A A' are I-bars forming the frame of the machine. 35 These support the entire structure. They are connected front and back by cross-bars, one of which forms the support for the operating mechanism and is shown in the detailed view, Fig. 5. The other is indicated partly 40 in section at R³ in Fig. 1. B' B² are the supporting devices for the interleaved sets of grate-bars, (marked C' C², respectively.) The supporting-bars B' B² are the inner two and move in unison. B² B² are the outer bars and 45 also move in unison. Each of them carries on suitable lugs D cross-bars d, having projections d², upon which rest the grate-bars. (See Fig. 3.) The grate-bars I prefer not to make of uniform size throughout their 50 entire length, and inasmuch as the central portion of them usually burns out while the ends are still useful I divide them into longitudinal sections, as indicated by the joints c c. (Seen best in Fig. 1.) By examining Fig. 2 it 55 will be seen that the portions of the grate-bars nearest to the magazine are wider than those in the center and back of the furnace. Thus as the coal enters the furnace it is supported on a comparatively solid surface having 60 only narrow air-spaces between the bars, but is subjected to the heat of the fire and its gases are evolved and burn in the furnace, while the coal itself partially cokes. As it further proceeds into the furnace it arrives at

the part of the grate where the bars are narrower and there is more space between them, so that a considerable increase of oxygen is furnished, generating an intense heat. Latches N are provided, which substantially fill the openings made by the dropping of the bars, as hereinafter described. These exclude any undue amount of air, and should the coal follow the bars and be carried back by them to too great an extent as they drop these latches will prevent its being withdrawn 75 from the fire and dropped into the pit.

As will be seen from Figs. 1 and 3, the frame of the machine is carried upon wheels A², which run upon tracks O O, so that it may be withdrawn as a unit from the furnace for 80 repairs. The supporting-bars B' B² are carried at their rear ends upon differential roller-bearings, one of which is shown at A³ in Fig. 1. As the supporting-bars B' B² are heavy, I counterbalance so much of their weight as is 85 desirable by springs b' b², (seen best in Figs. 1 and 3,) which are provided with turnbuckles b⁷. Enough of their weight must be left unbalanced to cause them to move by gravity with certainty.

The operating mechanism will be best understood from Fig. 4 in conjunction with Figs. 2 and 3. In Fig. 4, G is a casting forming a cross-head attached to the piston-rod of the piston F, (see Fig. 1,) reciprocating in 90 the cylinder E. Any suitable power may be used to operate the mechanism. I prefer hydraulic pressure, because this can usually be provided without undue expense and because the action of electric rotary mechanisms must be geared down to an objectionable extent to make them operate slowly enough; but the latter may be employed, if desired. Attached to the cross-head G are two inclines G' G², provided with lips g. The 100 ends of the supporting-bars B' B² are similarly inclined and are provided with lugs b³ b⁴ on the bar B' and b⁵ b⁶ on the bar B². These lugs coöperate with guides A⁴ A⁵, secured to fixed portions of the mechanism. 110 The guide A⁴ coöperates with the lugs b⁶ on the bar B², as shown in Figs. 1, 2, 3, and 4, while the lug b³ coöperates with one of the guides A⁵, as seen in Figs. 1, 2, and 3. The lugs b³ b⁶ overlap and coöperate with one another, as best seen in Figs. 2 and 3 and as 115 presently more fully explained.

Fig. 5 shows the supporting device for the cylinder and cross-head and the attached parts of the latter. The reference-letters refer to parts already described, and a detailed description is unnecessary.

Fig. 6 is a diagram which shows the motion of a point near the front end of the grate-bars. It is manifest from a consideration of 125 the drawings, particularly Fig. 1, that this diagram applies only to some selected point upon the front end of the bars and not to

their entire length in the rear, since they are supported upon the roller A³, and therefore do not rise and fall at that point, their motion being there substantially entirely longitudinal, while beyond that point the vertical movements are reversed in direction, the ends of the bars instead of being dropped away from the fire being (as already pointed out in my statement of invention) thrust up into it.

In Fig. 7, P illustrates a part of the mechanism of the ash-conveyer. (See also Fig. 1.) This acts to bring the ashes forward to the front of the pit. P' is the shank. P² is the lower part or bar, which is hinged to the upper one and carries the shovel P³. A lug p on the bar P², engaging with the back of shank P', permits the shovel to drag over the ashes as the mechanism passes toward the back of the furnace, but causes it to bring the ashes along as it is retracted. It is manifest that the direction of the movement of the ash is according to the convenience of the engineer. In the drawings I have shown ash-pits both in front and rear; but ordinarily only one would be used. When using a pit in the rear, a screen L is attached to the framework of the machine, so that the draft would not be unduly affected by opening the ash-pit door. These details, however, form no part of my invention and are left to the discretion of the manufacturer.

The operation of the device as thus described is as follows: As seen in Fig. 1, the piston F has just completed its stroke, the parts being in the position shown in Fig. 4. As it starts away from the furnace the cross-head G carries with it inclines G' G² over the slides M M and the lips g g engage with the hooked ends of the bars B' B', retracting them, the lugs b⁴ passing under the lugs b⁵ on the bars B² B² and the lugs b³ passing under the fixed guides A⁵. The inclines move away from the bars B² B², leaving them supported by the lugs b⁶ upon the guides A⁴ A⁴. When the piston reaches the end of its stroke, the ends of the bars B' B' will be in advance of B² B², or to the left of them in Fig. 2. The piston now moves toward the furnace, carrying with it the cross-head G and inclines G' G². The first effect of this motion is to raise the ends of the bars B' B' until they are in the same plane as the bars B², bringing all the grate-bars into the same horizontal plane, or substantially so, and engaging the rear faces of the lugs b⁴ on the bars B' with the front faces of the lugs b⁵ on the bars B². All the bars are then carried along for half the stroke of the piston. The bars B' B' then engage by the lugs b³ b³ with the upper surface of the guides A⁵ A⁵, the lugs b⁴ b⁴ being in front of and engaging with the lugs b⁵ b⁵ on the bars B² B², and a little later the lugs b⁶ on the bars B² B² reach the ends of the guides

A⁴ A⁴, and these bars are then depressed, as the others take their places upon the guides A⁵ A⁵. The piston is again at the right-hand end of its stroke, as seen in Fig. 1, but now the bars B² B² are depressed and B' B' are elevated, as shown in Fig. 4^a. The piston F now starts again toward the left, or away from the furnace, carrying with it the inclines G' G², the lips g upon which engage with the hook ends of the bars B² B². The lugs b³ b³ upon the bars B' B' rest in their turn upon the guides A⁵ A⁵. (See Figs. 2 and 3.) These bars are therefore stationary during the further outward movement of the cross-head and the inclines G' G². When the piston reaches the end of its stroke on the left, or away from the furnace, the lugs b⁶ b⁶ on the bars B² B² are just in advance of the front faces of the guides A⁴ A⁴ and the lugs b⁵ b⁵ are in advance of and below the lugs b⁴ b⁴ upon the bars B' B'. The piston now starts toward the right, or toward the furnace, and the first effect of this motion is to elevate the ends of the bars B² B², so that the bottom of the lug b⁶ coincides in plane with the top of guide A⁴, and the rear face, or that on the right of the lug b⁵, is in advance of the front face, or that on the left of the lug b⁴ on the bar B'. Inasmuch as the faces of the inclines are not subjected to the heat of the fire, they may be freely lubricated with any good cylinder-grease, and the friction from the weight of the coal at the back of the furnace suffices to prevent premature longitudinal movement. The piston continuing this course. The lips at the top of the incline now engage with the ends of the bars B² B². They in turn (by the lugs, as already pointed out) engage with the bars B' B', and thus all of the fire-supports are forced toward the back of the furnace until the piston again arrives at the right end of the cylinder, as seen in Fig. 1. In the meantime the bars B' B' have passed so far forward that the lugs b³ b³ have dropped off the guides A⁵ A⁵, the lugs b⁶ b⁶ have taken their places upon the guides A⁴ A⁴, as shown in Fig. 4, and the cycle of operation is complete.

The action of the ash-conveyer, it is believed, is evident without detailed explanation.

I believe it to be new with me to combine reciprocating motion in a grate with an ash-conveying arrangement operated by the same motion to carry the ashes forward or back, as may be desired.

Changes may be made in the arrangements indicated without departing from my invention. The precise figure described by the grate-bars is unimportant. I believe the one which I have indicated to be substantially the only one which should be used in practice, because the mechanism to obtain other motions must necessarily be more

complex; but I do not mean to confine myself in that respect.

I have designated the particular outline described by a selected point on the fire-surface of the grate-bars as "four-motion feed" in analogy to the feeding device in a sewing-machine, which is well known by that name. It is only essential that this motion should be represented by a substantially straight-sided closed figure a straight side of which is coincident in plane with the fire-bed. In using the term "four-motion feed" I use it in an indicative sense, not meaning to exclude feeding motions, the outline of which is represented by other figures having different numbers of sides, provided that the straight side which the point describes is in contact with the fire, although I prefer the four-sided figure for the reasons just pointed out.

My invention does not limit me to the precise forms of the devices indicated in the drawings. The particular feature, which consists of the four-motion feed of the alternating sets of bars, may be applied to many forms of existing stokers with only such changes as are obvious to those skilled in the art. Chains or bars divided into any desired number of sets—steam, electric, or other power—may be used, and other changes may be made and still embody the invention.

None of these formal changes has been illustrated, since their embodiment is within the skill of any constructing engineer. For example, no valves for the control of the power driving the cylinder are illustrated or described. Any desirable connection of this character may be made by the engineer, and as they would necessarily vary with the class of power employed I have preferred not to illustrate them.

Having thus described my invention, what I claim, and desire to protect by Letters Patent of the United States, is—

1. In a mechanical stoker, the combination of a plurality of interleaved sets of grate-bars, with means for imparting a feeding motion simultaneously to the sets and for lowering and retracting the different sets separately.

2. In a mechanical stoker, the combination of a plurality of interleaved sets of movable grate-bars with means for imparting to the sets, simultaneously, a series of distinct motions to feed the fuel, and for lowering and retracting the different sets separately.

3. In a mechanical stoker, the combination of a plurality of interleaved sets of grate-bars with means for imparting a feeding motion in a common plane, simultaneously to the sets, and for lowering and retracting the different sets separately and in alternation.

4. In a mechanical stoker, the combination of interleaved sets of fire-supports, with means for imparting to them a motion the outline of which is a substantially straight-

sided closed figure, a straight side of which is coincident in plane with the bottom of the fire; the sets of fire-supports being moved forward simultaneously when thus coincident, and being lowered and retracted in alternation.

5. In a mechanical stoker, the combination of interleaved sets of fire-supporting devices with means for imparting thereto in alternation a "four-motion feed," the upper movement of one being partly coincident in plane with the upper movement of the other; the motions of the sets being simultaneous upon their upper lines of movement and successive in the other parts of their motion.

6. In a mechanical stoker, the combination of interleaved sets of fire-supports with means for imparting to them a motion, the outline of which is substantially a straight-sided closed figure, the motions of the fire-supports overlapping longitudinally and one of the sets being stationary while the other is retracted; whereby, during the longitudinal movement of the sets, they simultaneously advance the fire, and while any set is lowered and retracted, the fire is maintained stationary.

7. In a mechanical stoker, the combination with two sets of interleaved grate-bars, of means for imparting to the sets in alternation a "four-motion" feed; the motions of the sets of bars overlapping, in the upper parts of the movement being simultaneous and substantially coincident in plane with the bottom of the fire, and one set of bars being lowered and retracted while the other is maintained stationary.

8. In a mechanical stoker, the combination with interleaved sets of grate-bars, of means for moving the sets in alternation in such manner that similar points on the fire-supporting surface of the bars in different sets substantially describe overlapping trapezoids, the upper sides of which coincide in plane with the bottom of the fire; all of the sets moving forward together, and some remaining stationary while others are lowered and retracted.

9. In a mechanical stoker, the combination of a number of interleaved sets of grate-bars, means for causing all of the sets to move forward longitudinally in a common normal plane, means for lowering one set out of contact with the fuel and retracting it while maintaining the remainder of the bars stationary in the normal plane, means for restoring the retracted bars to the normal plane and causing all of the bars to move forward therein, and means for repeating with another set of bars the movements of the first set.

10. The combination, in a mechanical stoker, of interleaved sets of grate-bars with

means for advancing them all in a common plane when in contact with the fire, and means for keeping some of them stationary, and lowering and retracting others while out of contact with the fire.

5 11. The combination, with a mechanically-operated grate, having a reciprocating movement, of a reciprocating ash-conveyer consisting of a series of jointed shovels at-

tached to the grate support or supports and 10 operated thereby.

In witness whereof I have hereunto set my hand, this 10th day of April, 1903, in the presence of two witnesses.

WILLIAM SEATON, JR.
